ROOF TRIM PIECE FOR A VEHICLE

Jesse R. Birchard, Walled Lake, Mich., Albert D. Mortrud, Pompano Beach, Fla., and Ray C. Conner, Battle Creek, Mich., assignors, by mesne assignments, to The Cortez Corporation, Kent, Ohio, a corporation of Ohio

Original design application Sept. 20, 1968, Ser. No. 13,621. Divided and this application Feb. 26, 1969, Ser. No. 17,041

Term of patent 14 years

Int. Cl. D12—14

U.S. Cl. D14—6

FIG. 1

FIG. 2

FIG. 1 is a front elevational view of a roof trim piece or a vehicle embodying our new design; and

FIG. 2 is a left side elevational view thereof.

The portion in broken lines is shown for illustrative purposes only.

This is a divisional application of application Ser. No. 1,13621, filed Sept. 20, 1968.

We claim:

The ornamental design for a roof trim piece for a vehicle, as shown and described.
